UNITED STATES PATENT OFFICE.

JOHN W. WATSON, OF WAYNE, PENNSYLVANIA.

DESIGN FOR A RADIATOR FOR AUTOMOBILES AND OTHER VEHICLES.

50,638.

Specification for Design.

Patented Apr. 17, 1917.

Application filed January 27, 1917. Serial No. 145,003. Term of patent 14 years.

To all whom it may concern:

Be it known that I, JOHN W. WATSON, a citizen of the United States, residing at Wayne, in the county of Delaware and State of Pennsylvania, have invented a new, original, and ornamental Design for a Radiator for Automobiles and other Vehicles, of which the following is a specification, reference being had to the accompanying drawing, forming a part thereof.

The figure illustrated in the accompanying drawing shows a side elevation of a radiator

embodying my design wherein the front profile has its major portion inclined rearwardly from top to bottom of the radiator.

I claim:

The ornamental design for radiator for automobiles and other vehicles substantially as shown and described.
